The ornamental design for a flower pot cover, as shown and described.

DESCRIPTION

FIG. 1 is a perspective view of our new flower pot cover design;

FIG. 2 is a side elevational view thereof;

FIG. 3 is a top plan view thereof;

FIG. 4 is a bottom plan view thereof;

FIG. 5 is a side elevational view of the design of FIG. 1, the only difference being in the horizontal angle of the skirt; FIG. 6 is a side elevational view of the design of FIG. 1, the only difference being in the near vertical angle of the skirt; FIG. 7 is a side elevational view of the design of FIG. 1, the only difference being in the downward angle of the skirt; FIG. 8 is a perspective view of a second embodiment of our new flower pot cover design;

FIG. 9 is a side elevational view thereof;

FIG. 10 is a top plan view thereof;

FIG. 11 is a bottom plan view thereof;

FIG. 12 is a side elevational view of the design of FIG. 8, the only difference being in the horizontal angle of the skirt; FIG. 13 is a side elevational view of the design of FIG. 8, the only difference being in the near vertical angle of the skirt;

FIG. 14 is a side elevational view of the design of FIG. 8, the only difference being in the downward angle of the skirt; FIG. 15 is a perspective view of a third embodiment of our new flower pot cover design;

FIG. 16 is a side elevational view thereof;

FIG. 17 is a top plan view thereof;

FIG. 18 is a bottom plan view thereof;

FIG. 19 is a side elevational view of the design of FIG. 15, the only difference being in the horizontal angle of the skirt; FIG. 20 is a side elevational view of the design of FIG. 15, the only difference being in the near vertical angle of the skirt; and,

FIG. 21 is a side elevational view of the design of FIG. 15, the only difference being in the downward angle of the skirt. The flower pot has no substantial thickness
